UNITED STATES PATENT OFFICE

HARRY E. DOERR, OF ST. LOUIS, MISSOURI, ASSIGNOR TO SCULLIN STEEL COMPANY, OF ST. LOUIS, MISSOURI, A CORPORATION OF DELAWARE

BOLSTER END CONSTRUCTION

Application filed January 23, 1931. Serial No. 510,610.

This invention relates to improvements in truck bolster construction and particularly to the design of the ends of the bolster.

It has been customary to use box-section truck bolsters which have substantially rectangular ends adapted to be received in vertical guide openings of the truck side frames. The load upon the center of the bolster is transmitted through suitable springs to the side frames and the spring plank which ties together the side frames. The top portion of the bolster end has customarily been provided with openings which tend to reduce the weight and make the casting and cleaning of the bolster relatively more easy. It has been found, however, that if the opening at the top surface of the bolster end is cut in from the extreme end of the bolster that the sides of the bolster end tend to spread upon casting and if the openings in the top surface of the bolster end extend in the plane of the side frame, the mid-portions of the sides of the bolster ends which form the vertical guiding means, tend to spread upon casting.

It is an object of the present invention to so design the openings in the top wall of the bolster end that the above objections due to spreading of the sides of the bolster end do not occur.

It is a purpose of the present invention to so form the openings in the top surfaces of the bolster ends that the sides of the bolster ends are tied together at their extreme ends by a web of metal and also by a web of metal in the plane of the side frame.

Further objects and advantages of the present invention will be more readily apparent from the following description taken in connection with the attached drawings in which—

Figure 1 is a half plan view of a bolster having the improved end construction;

Figure 2 is a side view of the bolster illustrated in Figure 1;

Figure 3 is an end view of the bolster illustrated in Figures 1 and 2;

Figure 4 is a half plan view of a modified design of bolster;

Figure 5 is a side view of the bolster shown in Figure 4;

Figure 6 is an end view of the bolster shown in Figures 4 and 5;

Figure 7 is an end view partially in section of the bolster illustrated in Figures 4, 5 and 6 assembled with a side frame and 55 springs; and

Figure 8 is a longitudinal vertical section of the assembly of Figure 7.

Figures 1, 2 and 3 illustrate one form of truck bolster design including the improvements of the present invention. The bolster illustrated is of the lateral motion type for a four-spring truck. The bolster is generally indicated 10, having a center plate bearing 12 and including at its end a top wall 14, side walls 16 and a bottom wall 18. The side walls include vertical guide lugs 20. The bottom wall 18 is formed with transverse corrugations 22 whereby the bolster end rests upon rollers when assembled with the side frame. The side frame includes vertical guide portions 24 which cooperate with the vertical side walls 16 of the bolster end.

As shown in Figure 1, the top wall 14 of the bolster is provided with three openings, one 75 being a transverse opening 26 substantially rectangular but having curved ends and a pair of substantially square openings 28. The openings are so designed that a tying web 30 remains between the side walls of the bolster at the extreme end thereof and a center web of metal 32 extends between the side walls of the bolster in the plane of the side frame. The center portion of the bolster is strengthened by a vertical web 34 extending longitudinally of the bolster and formed as shown in dotted lines in Figure 2. A pair of transverse webs 36 are provided, as indicated in Figure 3, tying together the vertical rib 34 with the transverse web 32 of the top wall 90 of the bolster.

In casting a bolster of the design shown in Figures 1, 2 and 3 it is apparent that the dry sand core will not cause the side walls 16 to bulge at their center portions since the cooling of the web 32 will hold the side walls together. However, the provision of the three openings 26 and 28 sufficiently take care of reducing the weight of the bolster and make it easier to cast and clean the bolster. The 100

dotted circles 38 in Figure 1 illustrate the relative positions of the four springs through which the weight of the bolster is transmitted to the spring plank.

[5] In order to illustrate a design of bolster of a type adapted to cooperate with a seven-spring truck, I have shown one form in Figures 4, 5, 6, 7 and 8, in which the bolster generally is indicated 40, having a bolster end including a top wall 42, side walls 44 and a bottom wall 46. The top and bottom walls are tied together by vertical longitudinal ribs 48 and 50 which are offset from the longitudinal center line of the bolster. The top wall 42 of the bolster end has a pair of openings 52 and 54 centrally disposed with respect to the longitudinal center line of the bolster but offset from the transverse plane of the side frame so that a transverse web 56 remains which ties together the side walls of the bolster. The vertical ribs 48 and 50 extend from the bottom wall to the top wall 42 of the bolster and merge with the webs 60 and 64 extending parallel to the longitudinal center line of the bolster. In the spaces between the longitudinal webs 60 and 64 and the side walls 44 of the bolster additional openings may be provided, such as shown by the pair of openings 66 which are offset with respect to the center opening 52 and the openings 68 offset with respect to the central opening 64. The dotted circles 70 in Figure 4 illustrate the positions of the supporting springs.

Figures 7 and 8 illustrate the assembly of the bolster illustrated in Figures 4, 5 and 6 with a side frame and spring and roller means. This bolster design as well as that illustrated in Figures 1, 2 and 3 prevents the bulging of the side walls of the bolster end during casting and therefore it is not necessary to subsequently straighten the side walls of the bolster by a pressing operation in order that the bolster ends may properly fit the openings provided in the side frames.

45 I claim:

1. An end construction for a box type bolster including imperforate bottom and side walls and a top wall having openings spaced apart on each side of the plane of the cooperating side frame.

2. An end construction for a box-type bolster including imperforate bottom and side walls and a top wall having openings on each side of the plane of the cooperating side frame, said openings being formed to leave a web of metal at the end of the top wall of the bolster and a web of metal tying together the side walls of the bolster in the plane of the cooperating side frame whereby to prevent spreading of the side walls upon casting the bolster.

3. An end construction for a box type bolster including imperforate bottom and side walls, a top wall having a transverse opening spaced between the end of the bolster

and the plane of the cooperating side frame, said top wall also having a pair of openings on the other side of the plane of the cooperating side frame, said pair of openings being spaced apart at the longitudinal center line 70 of the bolster and a vertical rib extending from the bottom wall of the bolster end to the top wall between said pair of openings.

4. An end construction for a box type bolster including imperforate bottom and 75 side walls, a top wall having a plurality of openings on each side of the plane of the cooperating side frame, said openings being so formed as to leave a transverse web of metal tying together the side walls of the bolster at the extreme end of the top wall of the bolster and at the plane of the cooperating side frame.

5. An end construction for a box type bolster including imperforate bottom and side 80 walls, a top wall having a plurality of openings on each side of the plane of the cooperating side frame, said openings being symmetrically disposed and including a pair of openings on the longitudinal center line of the bolster and additional openings spaced transversely therefrom and adjacent the side walls of the bolster and a pair of vertical ribs extending from the bottom wall of the bolster to the top wall between the central openings and the side openings.

Signed at St. Louis, Missouri, this 19th day of January, 1931.

HARRY E. DOERR.
